APPARATUS FOR TRANSFERRING SHEETS

William W. Leach, Warren, Ohio

Application September 14, 1937, Serial No. 163,761

16 Claims. (Cl. 271—26)

This invention relates, as indicated, to apparatus for transferring sheets, but has reference more particularly to apparatus for transferring metal sheets and the like from a pile or stack of sheets to delivery means, such as pinch rolls, conveyors or the like.

In my Patent No. 1,625,085, granted April 19, 1927, there is disclosed a feeder for sheet metal or the like, in which the sheets are picked up and moved to the desired position by suction cups actuated by mechanism consisting principally of cams. The present invention is concerned primarily with sheet-transfer apparatus embodying a number of highly desirable improvements in the patented apparatus, whereby the handling of the sheets is considerably expedited and sheets of various lengths may be handled with equal facility.

Among other objects of the invention may be mentioned the provision in apparatus of the character described of fluid actuated means for moving the suction cups; means for controlling the speed of movement of the suction cups from the feed position to the delivery position and from the delivery position to the feed position; means for positively controlling the suction in the suction cups, and means for preventing entry of fluid into the suction cups and suction lines during under fluid pick-up of sheets.

To the accomplishment of the foregoing and related ends, said invention, then, consists of the means hereinafter fully described and particularly pointed out in the claims; the annexed drawings and the following description setting forth in detail certain mechanism embodying the invention, such disclosed means constituting, however, but one of various mechanical forms in which the principle of the invention may be used.

In said annexed drawings:

Fig. 1 is a plan view of the apparatus;

Fig. 2 is a side elevational view of the apparatus, with vacuum cups shown in a position in which they are about to pick up a sheet;

Fig. 3 is an elevational view of the apparatus, as viewed from the feed end thereof;

Fig. 4 is a fragmentary longitudinal cross-sectional view of the apparatus, taken on a line substantially indicated by the line 4—4 of Fig. 3;

Fig. 5 is a plan view, on an enlarged scale, of a portion of Fig. 1, showing portions of the mechanism for controlling the movement of the vacuum cups and the suction therein;

Fig. 6 is a cross-sectional view, taken on the line 6—6 of Fig. 5;

Fig. 7 is a view similar to Fig. 6, but with the

parts shown in the position they occupy when the vacuum cups are in the sheet delivering position, as shown in dotted lines in Figs. 2 and 4;

Fig. 8 is a view similar to Fig. 6, but with the parts shown in a position intermediate the positions of Figs. 6 and 7;

Fig. 9 is a cross-sectional view taken on the line 9—9 of Fig. 5, and showing the mechanism for controlling the movement of the vacuum cups;

Fig. 10 is a view similar to Fig. 9, but with the parts shown in the position they occupy when the vacuum cups are in the sheet delivering position;

Fig. 11 is a view similar to Fig. 9, but with the parts shown in a position intermediate the positions of Figs. 9 and 10;

Fig. 12 is a cross-sectional view, taken on the line 12—12 of Fig. 11;

Fig. 13 is a view partly in section and partly in side elevation, taken on the line 13—13 of Fig. 20 5, and showing the mechanism for controlling the suction in the vacuum cups;

Fig. 14 is a view similar to Fig. 13, but with the parts shown in the position they occupy when the vacuum cups are in the sheet delivering position;

Fig. 15 is a view similar to Fig. 13, but with the parts shown in a position intermediate the positions of Figs. 13 and 14;

Fig. 16 is a vertical cross-sectional view, taken on the line 16—16 of Fig. 3, showing the safety valve for one of the suction cups;

Fig. 17 is a side elevational view similar to Fig. 2, but showing the apparatus as arranged for transferring sheets to a conveyor moving transversely to the direction of transfer movement of the sheets, the apparatus embodying a modified arrangement of suction cups and supporting frame therefor;

Fig. 18 is a plan view of the apparatus shown in Fig. 17;

Fig. 19 is an elevational view of the apparatus shown in Figs. 17 and 18, as viewed from the fluid end thereof;

Fig. 20 is a longitudinal cross-sectional view, on an enlarged scale, taken on the line 20—20 of Fig. 19; and

Fig. 21 is a perspective view of one of the cross-fittings shown in Fig. 20.

Referring more particularly to that form of the invention shown in Figs. 1 to 16 inclusive, the apparatus consists of various means which are supported on a frame consisting of spaced base channels 1 and 2, angle uprights 3, 4, 5 and 6, angle cross-members 7, 8, 9 and 10 secured to

the uprights, vertically spaced pairs of angle guide-channel supports 11, 12, 13 and 14 which extend parallel with the base channels and are supported by the angle cross-members, and angles 15 and 16, which interconnect the guide-channel supports.

The apparatus, as stated, consists of various means which, for convenience, may be designated as means for transferring the sheets, means for controlling the speed of movement of the suction cups, and means for preventing entry of fluid into the suction cups and suction lines during under fluid pick-up of sheets. Each of these means will now be separately described.

15 *Means for transferring the sheets*

For the purpose of picking up and transferring the sheets from a pile or stack to delivery means, such as pinch rolls, conveyor, or the like, mechanism is provided, which is best shown in Figs. 1 to 4 and 9 to 12 inclusive.

Secured to the angles 11 and 12 are channels 17, each of which has a short vertically extending forward portion 18, a relatively long horizontally extending portion 19, and an arcuate curved portion 20 which interconnects the portions 18 and 19. Secured to the angles 13 and 14, and disposed in the same planes as the channels 18, are channels 21, which are similar to the channels 18, but somewhat longer than the latter, so that their vertical portions 22 are in a plane spaced forwardly of the plane of the vertical portions 18 of the channels 17. The channels 17 form trackways or guides for rollers (not shown) mounted on the ends of a shaft 23, and the channels 21 similarly form trackways for rollers (not shown) mounted on the ends of shafts 24, 25 and 26. The shaft 23 has pivotally secured thereto, just inwardly of the rollers thereon, curved supporting arms 27, having secured to the lower extremities thereof tubular posts 28. Secured to the posts 28 at vertically spaced points, as by means of set screws 29 are cross-fittings 30, which support tubes 31. Secured to the tubes 31, as by set screws 32, are cross-fittings 33, through which extend the vertical tubular supports 34 for the suction cups 35. The normal position of the supports, and consequently of the suction cups, is determined by the abutment of collars 35 with the lower fittings 33, these collars being secured to the supports by means of set screws 36. The supports may, however, yield slightly, as when the suction cups initially contact the uppermost sheet of a pile of sheets, and to permit such yielding, expansion coil springs 37 are provided, which surround the supports and at one end engage the upper fittings 33 and at the lower end engage the collars 35.

60 For the purpose of actuating the arms 27 so as to cause these arms to move from the position shown in solid lines to that shown in dotted lines in Fig. 4, thereby moving the suction cups from the sheet-feed or pick-up position shown in solid lines to the sheet delivery position shown in dotted lines in Fig. 2, mechanism is provided comprising a reciprocable rod 38, the forward end of which is pivotally secured to the shaft 24 intermediate the ends of the latter, a pair of links 39 pivotally interconnecting the shafts 24 and 25, and a pair of links 40 pivotally interconnecting the shafts 25 and 26. The shaft 26, in turn, extends through the arms 27, so that any movement imparted to the rod 38 is communicated to the arms.

The rod 38 extends through the head 41 of a cylinder 42, and has secured to its rear end a piston 43 which works in the cylinder. The cylinder has secured to its rear end a head 44, which is similar to the head 41. The cylinder extends longitudinally of the apparatus and is supported by means of a pair of longitudinally extending bars 45, which in turn are carried by pedestal supports 46 mounted on the angle cross-members 9 and 10.

Air, for actuating the piston 42, is supplied by an air pressure tank P, the air passing from this tank through a conduit 47, pressure control valve 48, slide control valve 49, and into the cylinder through conduits 50 and 51, depending upon the position of the slide member 52 of the valve 49. The tank P is supplied with air from an outside source through a pressure regulating device R, a gauge G being also provided in the line for indicating the air pressure. The valve 49, as clearly shown in Figs. 1, 2 and 9 to 12 inclusive, is clamped to the cylinder intermediate the ends of the latter, and the conduits 50 and 51 extend from opposite sides thereof and into communication with ports 53 in the cylinder heads. The slide member 52 of the valve operates in a short cylindrical member 54 disposed within the valve and provided with spaced sets 55 and 56 of circumferentially spaced apertures. The member 55 also has a large aperture 57 therein intermediate the sets of smaller apertures. The slide member 52 of the valve is shaped similarly to a dumb bell, having ends of the same area as the internal area of the member 54 and an intermediate portion of reduced diameter. The valve 49 is also provided with laterally opening discharge ports 58 and 59, air inlet passage 60, a longitudinally extending passage 61 in which the member 54 is disposed, annular passages 62 and 63 which are in registry with the apertures 55 and 56 respectively, passages 64 and 65 extending radially of the passages 62 and 63 respectively, and discharge ports 66 and 67 respectively communicating with the conduits 50 and 51. The passage 61 is closed at the ends as by means of screw plugs 68 and 69.

The mechanism for actuating the valve slide-member 52 will now be described.

Secured to the cross-member 9 of the frame, and extending rearwardly thereof, and downwardly, is a bracket 70, in the lower end of which is journalled a rock shaft 71. Journalled on this shaft for oscillatory movement thereabout is an arm 72 having a pair of semi-circular recesses 73 and 74 in its upper end, forming seats for a latching roller 75, mounted in the end of a latching lever 76. Lever 76 is pivotally mounted on the bracket 70, as at 77, and is normally urged downwardly by means of a coil spring 78, so as to maintain the roller 75 in either the recess 73 or 74. The coil spring 78 is secured to the lever intermediate the ends of the latter, and is adjustably secured to a laterally extending flange of the bracket by means of a bolt 79. A rod 80 interconnects the arm 72 with the valve slide member 52, so that oscillation of the arm results in reciprocal movement of said valve member.

The shaft 71 has keyed thereto an arm 81, which, upon rocking movement of the shaft, alternately contacts screws 82 and 83, which are adjustably mounted in lugs 84 and 85 respectively extending from the arm 72. In this way, 75

the arm 72 is oscillated between the extreme positions shown in Figs. 9 and 10.

Rocking movement of the shaft 71, for the purpose of oscillating the arm 72, and for certain other purposes to be presently described, is effected by the mechanism shown in Figs. 5 to 8 inclusive. Such mechanism comprises in part a rod 86 which extends through the cross-member 9 of the frame and has fixedly secured thereon at longitudinal spaced points curved arms 87 and 88. The rod 86 is pivotally connected at its rear end to a lever 89, the lower end of which is keyed to the shaft 71. The rod 86 is moved as the piston 43 approaches the forward and rearward limits of its movement, and in response to the movement of other parts of the apparatus, as will presently appear.

Means for controlling the speed of movement of the suction cups

It is desirable, particularly when delivering sheets to a pair of pinch rolls which are driven at constant peripheral speed, to deliver the sheets to such rolls at a speed corresponding with such peripheral speed. In order to permit sheets to be delivered to the pinch rolls at such speed, irrespective of the length of the sheets, it becomes necessary to vary the speed of movement of the vacuum cups from the feed position to a position somewhat in advance of the delivery position, and from the delivery position back to the feed position.

By controlling these speeds independently of each other, it has been found that sheets in a large variety of sizes and lengths can be satisfactorily handled without variation in the speed of the pinch rolls, so that the sheet transferring operations can be considerably expedited.

For the purpose of thus controlling these various speeds, mechanism is employed, which is best shown in Figs. 1 to 4 inclusive.

Mounted on the bars 45 is a tank or receptacle 90 having a removable cover 91. Disposed within this tank are upright cylinders 92 and 93, which are open at the top, and within which work pistons 94 and 95 respectively. A rock shaft 96 is journaled in the sides of the tank and has keyed thereto intermediate its ends a walking beam 97, the ends of which are pivotally connected to rods 98 and 99, the rod 98 being pivoted to the piston 94 and the rod 99 being pivoted to the piston 95. The shaft 96 is adapted to be oscillated through the medium of links 100 and 101, and levers 102 and 103. The links 100 and 101 are pivotally secured at their forward ends to the shaft 24 and at their rear ends to the lower ends of the levers 102 and 103 respectively, the upper ends of the levers being keyed to the ends of the shaft 96. Reciprocal movement of the shaft 24 will thus result in movement of the pistons 94 and 95 within their cylinders.

The tank 90 is filled to the level indicated in Fig. 4 with oil or similar fluid, the oil filling the cylinders 92 and 93. Upon rearward movement of the shaft 24, the piston 94 will move downwardly in its cylinder, forcing oil out of the cylinder through discharge ports 104 and 105 which are disposed at different levels. The cylinder 92 is also provided with a check valve 106, which is closed during the downward movement of piston 94. Since the oil is thus discharged through relatively small outlets, a resistance to the movement of the piston is set up, and the speed of rearward movement of the shaft 24, and consequently of the suction cups, is thereby controlled. The

resistance to movement of the piston and consequently the speed of the rearward movement of the suction cups may be varied by partially closing the ports 104 and/or 105 by means of slide valve rods 107 and 108. These rods extend through the cover 91 and may be separately manipulated or adjusted by means of handwheels 109 and 110.

For the major portion of the downward movement of the piston 94, oil is discharged through both ports 104 and 105, so that the speed of the suction cups will depend on the setting of both valve rods 107 and 108. As the suction cups approach a position about a foot or so in advance of the pinch rolls, however, the piston 94 closes the discharge port 104, and thereafter, the speed of the cups will depend solely on the setting of the valve 108. Upon upward movement of the piston 94, oil is drawn into the cylinder 92 through the check valve 106 as well as the ports 105 and 104.

At the same time that the piston 94 is descending, the piston 95 ascends in the cylinder 93, drawing oil into the cylinder through a check valve 111 and port 112. The piston 94 moves downwardly upon the return of the suction cups to their initial or feed position, and the speed of this movement, similarly to the movement of the piston 94, is controlled by the area of the outlet through port 112, which area may be varied by means of a slide valve rod 113. The rod 113 extends through the cover 91 and may be controlled by means of a hand-wheel 114.

By suitable manipulation of the valves 107, 108 and 113, an infinite variety of speeds of the suction cups may be obtained, as will be readily understood.

It may be noted at this point that the pin 115 which connects the link 100 and lever 102 has mounted on its outer end a cylindrical member 116 which engages and moves the arm 88 to the position shown in Fig. 6 at the conclusion of the rearward movement of the suction cups, thereby moving the valve member 52 to the position shown in Fig. 9. It may also be noted that the shaft 24 is provided adjacent one end with a cylindrical member 117 which engages and moves the arm 87 to the position shown in Fig. 7 at the conclusion of the forward movement of the suction cups, thereby moving the valve member 52 to the position shown in Fig. 10.

Mechanism for controlling the suction in the suction cups

For the purpose of controlling the suction in the suction cups, mechanism is provided which is best shown in Figs. 1, 2, 3, 5 to 8 inclusive, and 13 to 16 inclusive.

This mechanism comprises a vacuum tank V, in which a vacuum or suction is maintained by means of a vacuum pump 120, the piston 121 of which is reciprocated by means of a motor 122, endless belt 123, fly-wheel 124, shaft 125, and crank disk 126. The shaft 125 is journaled in bearings 127 and 128 which are secured to the angle uprights 3 and 5 of the frame, and the upper roller 120 of a pair of pinch rolls is keyed to and therefore driven by this shaft. The lower roller 130 of the pinch rolls is in frictional engagement with the roller 129 and is normally urged into such engagement by means of springs 131, which bear against the ends of the roller 130.

Suction is applied to the cups 35 through conduits 132 and 133, slide control valve 134, flexible conduit 135, manifold 136, and flexible tubu-

lar connections 137, which interconnect the manifold with valve casings 138 threadedly secured to the upper ends of the tubular supports 34 (see Fig. 16). The manifold 136 is carried by brackets 139 which extend from the bar 31.

The degree of vacuum in the suction cups is determined by a mercury column gauge 140 (Fig. 2).

The valve 134 is mounted on a bracket 141 secured to angle 14, and, as shown in Fig. 13, comprises a cylindrical body having an inlet opening 142 and an outlet opening 143. Mounted for sliding movement with this body is a slide member 144 having an annular recess 145 in its periphery, forming a passage which, as shown in Fig. 13, intercommunicates openings 142 and 143. The member 144 has an opening 146 in one end communicating with a radially extending passage or opening 147 which is spaced longitudinally 20 from the recess 145.

The member 144 has pivotally secured to its rear end a connecting rod 148, which, in turn, is pivotally secured at its rear end to an arm 149 of a lever 150. This lever is loosely journalled on a pin 151 which is mounted in a bracket 152 secured to frame angle 14 and has a forwardly extending arm 153 and a rearwardly extending arm 154. The arm 153 has a pair of semi-circular recesses 155 and 156 in its end, forming seats 30 for the cylindrical end 157 of a latching lever 158. Lever 158 is keyed to a shaft 159 which is journalled in a bracket 160 secured to frame angle 9. The arm 153 also has a flattened portion 161 intermediate the recesses 155 and 156. The lever 158 is normally urged in a clockwise direction as shown in Fig. 13, so as to maintain the end 157 thereof in one or the other of the recesses 155 and 156. This is accomplished by means of a coil spring 162, which at its upper 40 end is adjustably secured to frame angle 9 and at its lower end to a lever 163, the latter being keyed at its rear end to the shaft 159.

The lever 150 is adapted to be oscillated by means comprising a lever 164, keyed to shaft 71 and a link 165, the link being secured at its upper end to the arm 154 of the lever. In order to cushion the movement of the various parts, the connection between the lever 164 and the link 165 is effected through coil springs 166 and 167 which are mounted within a rectangular box-like portion 168 of the link 165, on a pin 169 extending through the portion 168 of the link, these springs bearing at their inner ends against a lateral extension 170 of the lever 164.

It will be apparent from the foregoing description that oscillation of the shaft 71 will result in reciprocal movement of the valve members 144.

Means for preventing entry of fluid into the suction cups and suction lines during under-fluid pick-up of sheets

For the purpose of preventing entry of fluids, such as pickling liquors into the suction cups when the cups enter a tank in which the fluids are contained, so as to avoid any possibility of such fluids finding their way into the suction line when suction in the cups is resumed, means are provided which are best shown in Figs. 1, 5, 6, 7, 8, 13, 14, 15 inclusive.

Such means comprises an arm 171 of lever 89, provided with an arc-shaped end portion 172 having an arcuate slot 173 therein forming a track or guideway for a pin 174 extending laterally from one end of a rod 175. The opposite end 75 of rod 175 is pivotally secured to a pin 176, which

extends from a disc 177 secured to the upper end of lever 102. The pin 176 is disposed eccentrically of the disc 177, but the latter is concentric with the lever 102. The operation of this mechanism will be presently described.

Should any fluid inadvertently rise into the tubular posts 34 during application of suction to the cups, as when a sheet is missed or drops off the cups due to the weight thereof, such fluid will strike a valve 178 (Fig. 16), forcing said valve against a diaphragm 179 within the valve casing 138, thereby closing off suction inlet ports 180, and preventing entry of the fluid into the suction lines.

Method of operation

Having now described in detail the construction of the apparatus and the principal features thereof, the function of the apparatus will be best understood by a description of the various movements which the apparatus undergoes during one complete cycle of operations.

It will be assumed for this purpose, that sheets are to be transferred from a pile of sheets which are located in a pickling tank T containing a pickling liquor L, to the pinch rolls 129 and 130, to be delivered by the latter onto a table T', a conveyor or the like.

With the valves 107, 108 and 113 properly set, as determined by the speed of the pinch rolls and the length of the sheets to be delivered thereto, and the suction cups 35, as shown in Fig. 2, in a position to pick up the top-most sheet of the pile S, the valve member 144 of the valve 134 is in the position shown in Fig. 13, being maintained in this position by the latching lever 158, the end 157 of which is disposed in the recess 156 of the arm 153. With the member 144 in this position, suction is applied to the cups 35, since the openings 142 and 143 of the valve are in communication with each other by way of the annular recess 145. With the suction thus applied, the uppermost sheet of the pile is ready to be picked up.

At the same time that the suction is thus applied, the valve member 52 of the valve 49 is moved by the rod 80 to the position shown in Fig. 9, being maintained in this position by the latching lever 76, the roller 75 of which is disposed in the recess 74 of the arm 72. With the member 52 in this position, air will flow from the tank P into the left-end of the cylinder 42, as viewed in Fig. 4, by way of conduit 47, inlet passage 60, aperture 57, the annular space between the intermediate portion of the valve member 52 and the interior wall of member 54, apertures 55, annular passage 62, passage 64, port 66, conduit 50, and port 53. In this way the piston 43 is moved in the cylinder to the position shown in dotted lines in Fig. 4, thereby moving the suction cups and the sheet held thereby to the sheet delivery position shown in dotted lines in Fig. 2, in which position the forward end of the sheet is gripped by the pinch rolls and drawn therethrough upon release of the sheet by the suction cup. During this movement of the piston 43, the air ahead of the piston is discharged into the atmosphere by way of port 53, conduit 51, port 67, passage 65, annular passage 62, apertures 56 and discharge port 59.

Near the end of the aforesaid movement of the piston 43, the member 117 engages the arm 87 on the rod 86 and moves this arm to the position shown in Fig. 7, as a result of which the valve member 144 is moved to the position shown in

Fig. 14, being maintained in this position by the latching lever 158, the end 157 of which is disposed in the recess 155 of the arm 153. In this position of the valve member, the suction in the cups 35 is cut off and air enters the cups by way of opening 146, 147 and 148, thereby releasing the sheet from the cups.

At the same time that the suction is thus cut off, the valve member 52 is moved by the rod 80 to the position shown in Fig. 10, being maintained in this position by the latching lever 76, the roller 75 of which is disposed in the recess 73 of the arm 72. With the member 52 in this position, air will flow from the tank P into the right end of the cylinder 42, as viewed in Fig. 4, by way of conduit 41, inlet passage 60, aperture 51, the annular space between the intermediate portion of the valve member 52 and the interior wall of member 54, apertures 56, annular passage 63, passage 65, port 67, conduit 51 and port 53. In this way the piston 43 is moved to its initial position in the cylinder, thereby moving the suction cups to the sheet feed position shown in Fig. 2, in which position another sheet may be picked up from the pile S. During this movement of the piston 43, the air ahead of the piston is discharged into the atmosphere by way of port 53, conduit 50, port 66, passage 64, annular passage 62, apertures 55 and discharge port 58. Near the end of the aforesaid movement of the piston, the member 116 on the pin 115 engages and moves the arm 88 on the rod 86 to the position shown in Fig. 6, as a result of which, the valve member 144 is moved to the position shown in Fig. 13, in which position of the valve member, suction is again created in the cups 35.

When the levers 101 and 102, during their return to their initial position (Fig. 6) have returned to a half-way position, as shown in Fig. 8, the arm 171 of lever 89 is swung from the position shown in Fig. 7 to that shown in Fig. 8, thereby rocking the shaft 71 to an extent sufficient to swing the arm 153 of lever 150 to the position shown in Fig. 15, the lever 150 being maintained in this position by virtue of the engagement of the end 157 of the latching lever 158 with the flattened portion 161 of the arm 153. The movement of the arm 153 is sufficient to move the valve member 144 of valve 134 to the position shown in Fig. 15. In this position of the valve member 144, the opening 143 of the valve is closed by the valve member, so that the air which is in the suction cups is trapped therein. Since the air in the cups remains thus trapped from this point until the cups engage the uppermost sheet of the pile of sheets in the pickling tank, none of the pickling liquor can enter the cups, and be drawn into the suction lines when suction is subsequently applied to the cups.

As a result, the danger of impairment or destruction of the suction is avoided, and, at the same time, no portions of the apparatus, other than the rubber suction cups themselves, can be attacked by the pickling liquors.

When the parts are subsequently moved by the member 116 to the position shown in Fig. 6, the pin 174 does not interfere with this movement, as the arc-shaped portion 172 of the arm 171 of lever 89 merely slides over the pin, the pin occupying a position intermediate the ends of the slot 173, as clearly shown in Fig. 6. Moreover, the position of the valve member 52 of valve 49 during this interval is not disturbed, as it is necessary, in order to move this valve member from the position shown in Fig. 11 to the position shown in Fig. 9,

to rock the arm 72 sufficiently to cause the roller 75 to ride over the hump between the recesses 73 and 74 and into the recess 75.

Modification

Due to the construction of the apparatus, it may be readily adapted for the transfer of sheets to a conveyor moving transversely of the apparatus.

For this purpose, the pinch rolls and associated driving mechanism shown in Fig. 2 of the drawings, are removed, and a conveyor, designated C, is disposed as indicated in Figs. 17, 18 and 19, the conveyor moving transversely of the apparatus, so as to deliver sheets transferred thereto to a point spaced laterally of the apparatus.

In order to facilitate the transfer of sheets from the pile S' to such conveyor C, a modified arrangement of suction cups and supporting frame therefor is employed, as shown in Figs. 17 to 21.

Referring to these figures of the drawings, it will be seen that the tubular posts 28, in this case, are provided at vertically spaced points with cross-fittings 181, through the horizontal openings of which extend tubes 182, these tubes extending longitudinally of the apparatus and being secured in position by means of set screws 183. These tubes are provided at their ends with cross-fittings 184, to which are secured tubes 185 extending transversely of the tubes 182. Each of the tubes 185 carries three cross-fittings 186, through the vertical openings of which extend the tubular supports 187 of suction cups 188. The cups 188 are evacuated in the same manner as the cups 35, so that further description of the means for evacuating the cups is believed to be unnecessary.

It will be apparent that the position of the suction cups may be easily adjusted in accordance with the dimensions of the sheets.

Instead of utilizing air under pressure for operating the piston 43, steam or a similar medium may be employed.

Other modes of applying the principle of my invention may be employed instead of the one explained, change being made as regards the mechanism herein disclosed, provided the means stated by any of the following claims or the equivalent of such stated means be employed.

I therefore particularly point out and distinctly claim as my invention:

1. In apparatus of the character described, suction cups for transferring sheets from a sheet-feed position to a sheet-delivery position and from the sheet-delivery position back to the sheet-feed position, fluid-actuated means for thus moving said suction cups, and valve-controlled fluid means whereby the speed of movement of the cups to a position intermediate the feed and delivery position, the speed of movement of the cups from said intermediate position to the delivery position, and the speed of movement of said cups from the delivery position back to the feed position, may be independently varied.

2. In apparatus of the character described, suction means adapted to grip a sheet, a cylinder, a piston in said cylinder, means interconnecting said piston and suction means, and fluid means for actuating said piston in two directions, whereby to move said suction means between a sheet-feed and a sheet-delivery position and between the sheet-delivery and sheet feed position.

3. In apparatus of the character described, a tank containing sheets and a pickling fluid, a sheet-delivery station, suction cups for transfer-

- ring said sheets from said tank to said station, means for returning the cups to said tank, and means for excluding said pickling fluid from entrance into said cups during the entry of the cups 5 into the fluid.
4. In apparatus of the character described, a tank containing a pickling fluid and sheets to be pickled, suction cups adapted to enter said fluid and to be evacuated so as to seize one of said 10 sheets, and means operative during entry of said cups into said fluid for trapping the air in said cups, whereby to exclude said fluid from said cups.
5. In apparatus of the character described, suction cups, means for alternately evacuating said cups and admitting air thereinto to break the vacuum, and means operative during the air admission cycle for trapping in said cups the air thus admitted thereinto.
- 15 6. In apparatus of the character described, suction cups, means for moving said cups into a fluid, and means for excluding the entrance of said fluid into said cups during said movement.
7. In apparatus of the character described, suction cups, means for moving said cups into a fluid, and means for trapping air in said cups during said movement, whereby to prevent said fluid from entering said cups.
- 20 8. In apparatus of the character described, suction cups adapted to grip a sheet to be transferred from one position to another, said cups adapted to be returned to their initial position, means for thus moving said cups, and means for braking the movement of said first-named means.
9. In apparatus of the character described, means for transferring sheets from a sheet-feed position to a sheet-delivery position and from the sheet-delivery position back to the sheet-feed position, means for thus moving said transfer means, and means whereby the speed of 25 movement of said first-named means from the sheet-feed to the sheet-delivery and from the sheet-delivery to the sheet-feed position may be independently varied.
- 30 10. In apparatus of the character described, suction means for transferring sheets from a sheet-feed position to a sheet-delivery position and from the sheet-delivery position back to the sheet-feed position, means for thus moving said suction means, and means for independently varying the speed of movement of said suction 35 means from the sheet-feed to the sheet-delivery position and the speed of movement of said suc-
- tion means from the sheet-delivery to the sheet-feed position.
11. In apparatus of the character described, suction means for transferring sheets from a feed position to a delivery position, a cylinder, a piston in said cylinder, means interconnecting said piston and said suction means, and means acting directly on said piston for reciprocating said piston in said cylinder, whereby to cause movement of said suction means between said 40 positions.
12. In apparatus of the character described, suction cups adapted to grip a sheet to be transferred from one position to another, said cups adapted to be returned to their initial position, means for thus moving said cups, fluid means for braking the movement of said first-named means, and means for varying the degree of braking.
13. In apparatus of the character described, suction cups adapted to grip a sheet to be transferred from one position to another, said cups adapted to be returned to their initial position, means for thus moving said cups, and valve-controlled fluid means for braking the movement of 45 said first-named means.
14. In apparatus of the character described, suction cups, means for moving said cups from a sheet-feed position to a sheet-delivery position to the sheet-feed position, and means responsive 50 to the movement of said first-named means for creating and destroying suction in said cups.
15. In apparatus of the character described, suction cups, means for moving said cups from a sheet-feed position to a sheet-delivery position and back to said sheet-feed position, and means responsive to the movement of said first-named means for creating suction in said cups prior to their movement to said sheet-feed position and for destroying suction in said cups when 55 said cups are substantially in the sheet-delivering position.
16. In apparatus of the character described, a tank containing a pickling fluid and sheets to be pickled, suction cups adapted to enter said fluid and to be evacuated so as to seize one of said sheets, means for moving said cups from said tank to a sheet-delivery position, and back to said tank, and means responsive to the movement of said cups back to said tank for trapping the air in said cups, whereby to exclude said fluid from said cups.

WILLIAM W. LEACH.
